UNITED STATES PATENT OFFICE.

McCLELLAND MYERS, OF SAN FRANCISCO, CALIFORNIA, ASSIGNOR TO HENRY M. SCIPLI
OF SAN FRANCISCO, CALIFORNIA.

GLASS-MOLDING APPARATUS.

No. 862,003.

Specification of Letters Patent.

Patented July 30, 1907.

Application filed April 17, 1906. Serial No. 312,160.

To all whom it may concern:

Be it known that I, McCLELLAND MYERS, a citizen of the United States, residing at San Francisco, in the county of San Francisco and State of California, have 5 invented certain new and useful Improvements in Glass-Molding Apparatus, of which the following is a specification.

This invention relates to glass molding apparatus and is in the nature of an improvement upon the construction disclosed in my prior patents Nos. 809,969 and 810,375, both granted January 16, 1906, the object of the present invention being to simplify and improve the construction disclosed in said patents and materially increase the output of the machine, which is de- 10 signed to form threads on glass caps for fruit and other jars and bottles, or for glass, china or porcelain receptacles which are required to be hermetically sealed.

By means of the construction hereinafter described, the output or capacity of the machine is increased several fold as compared with the apparatus set forth in my said prior patents.

With the above and other objects in view, the nature of which will more fully appear as the description proceeds, the invention consists in the novel construction, 25 combination and arrangement of parts, hereinafter more fully described, illustrated and claimed.

In the accompanying drawings, Figure 1 is a side elevation of the glass molding apparatus of this invention. Fig. 2 is a vertical sectional view of the same. 30 Fig. 3 is a plan view thereof. Fig. 4 is a sectorial plan view of the same.

The apparatus or machine contemplated in this invention comprises a base or bed-plate A, and the same may be mounted upon truck-wheels, as shown, for 35 facilitating the movement of the machine as a whole from place to place.

Extending upward centrally from the bed-plate A is a king post or central column B, the same being fastened permanently to the bed-plate and extending upward a suitable height where it is provided with a horizontally extending bracket arm 18.

Supported by the outer end of the bracket arm 18 is a cylinder 2, in which is mounted a piston C which carries a piston rod 7 having at its lower end a plunger 45 or presser-head 3, by which molten glass is compressed in the mold hereinafter described. The cylinder is provided with the usual stuffing boxes at opposite ends thereof.

The column or post B may be made in several sections superimposed one upon the other and bolted or otherwise fastened together, as at b, and at a suitable elevation, said column is provided with a table support 50 16 which may be in the form of a circumferential flange, said support being provided with an annular groove in its upper face in which are received antifriction balls

b' which also work in an annular groove in the bottom or a turn-table 17 which encircles the column B, the said turn-table being thus adapted to rotate upon a vertical axis formed by the column B.

The turn-table 17 carries on its upper side a plurality 60 of molds each consisting of a cup member 6 and a plug or mandrel member 4, the latter being shown in Fig. 2 as exteriorly threaded and tapered and carried by a cap-plate D which is supported on the upper ends of a series of supporting posts 5, the lower ends of which are 65 firmly connected to the turn-table 17. The plug member 4 may be supported at any desired elevation above the top of the turn-table 17 by the means described.

Each mold member 6 is mounted fast upon the upper 70 end of a mold-actuating spindle 13, the lower end of which is reduced to provide oppositely disposed flat sides adapted to be engaged by a turning chuck 9 hereinafter particularly referred to. The spindle 13 is threaded, as shown at d, and is received in an internally 75 threaded bushing d' secured to and extending downwardly from the turn-table 17, as clearly shown in Fig. 2. It will thus be seen that by rotating the spindle 13, the mold member 6 will be raised or lowered according to the direction in which said spindle is turned by means 80 of the chuck 9.

It will be observed that the plug member is centrally apertured, as shown at d'' to admit of the passage of the presser-head 3 in compressing the glass in the mold after the mold member 6 has been elevated in the manner described. The spindle 13 is provided with a central longitudinal bore in which is slidingly received the stem 14 of an ejector, said stem being provided with a conical ejector head E which is countersunk in the bottom of the member 6 so as to lie flush therewith, as shown in 90 Fig. 2, and form a normally imperforate floor for the said member 6.

A plurality of chucks 9 and 10 is employed, each of said chucks comprising oppositely arranged and rigidly related jaws carried by the upper end of a vertical shaft 95 F mounted in a suitable bearing connected with the bed-plate A. Two of such chucks are shown in the drawings and the shafts thereof are provided with beveled gear wheels 7 and 8 which mesh with and are driven by beveled gear wheels 7' and 8' on a horizontal 100 chuck operating shaft 11 which is mounted in suitable bearings on the bed-plate A, as shown in Fig. 4. The shaft 11 is constantly in gear with the shafts F so that when the shaft 11 is revolved, motion is simultaneously transmitted to the vertical shafts carrying the chucks 9 105 and 10.

The shaft 11 is driven by a spur gear wheel 12 on a short counter shaft G also mounted in suitable bearings on the bed-plate, as shown in Fig. 4, said gear 12 meshing with a pinion on the shaft 11. The shaft G is pro- 110

vided with a ratchet wheel *g* with which a pawl *g'* engages, said pawl *g'* being pivotally mounted on a collar *H* carried by and mounted upon the piston rod *h* of the piston of a cylinder 22 shown in Figs. 1 and 4. It will thus be seen that as the piston rod *h* is reciprocated, the pawl carried thereby actuates the ratchet wheel on the countershaft *G*, and by means of the gearing 12, motion is transmitted to the chuck actuating shaft 11; thereby rotating both of the chucks 9 and 10 simultaneously and causing them to act upon the overlying mold actuating spindles for elevating or lowering the mold members 6, as the case may be.

Arranged at a suitable point on the bed-plate *A* is a cylinder 23 having an upwardly extending piston rod 15 which, when the table is locked by means hereinafter described, lies directly beneath one of the ejector stems 14. When the piston of the cylinder 23 is moved upward, it operates on the stem 14, lifting the ejector and ejecting the molded glass article from the mold.

20 The means for locking the turn-table to prevent movement thereof while the glass articles are being molded and ejected, consists of a latch 20 in the form of a rod extending vertically upward within a suitable stand or bearing post 21. The upper end of said latch 25 is tapered, as shown in Fig. 2, and is receivable in any one of a series of socket openings *I* in the turn-table 17, the latch being normally upheld by a supporting spring *i* shown in Fig. 2. Arranged beneath the bed-plate *A* is a latch depressing lever 19 which is fulcrumed on the 30 bed-plate at one end and connected at a point intermediate its ends to the latch 20, said lever extending outward beyond the bed-plate *A* where it is provided with a suitable foot-piece or treadle 19', as shown. At any time desired, the operator may depress the lever 19 35 and move the latch 20 downward to release the turn-table which may then be turned until the latch 20 snaps into the succeeding opening or socket *I* in the table, when the molds will be properly positioned relatively to the presser-head 3 and the ejector piston of the cylinder 23.

40 *K* designates a four-way valve from which supply and exhaust pipes 24 and 25 lead to the cylinder 2, while other pipes 26 and 27 lead to the cylinders 22 and 23 respectively. Air or steam may be supplied to the cylinders for actuating the pistons thereof.

The operation of the apparatus may be briefly described as follows: When the turn table 17 is in the position shown in Figs. 1 and 2, the cup member 6 has been elevated by the beveled gear 8 after the glass has been 50 placed within said cup and the shaft 11 has been rotated to hold the glass against the threaded plug 4. The turn table 17 is then rotated toward the left, the spindle 13 moving out of the turning chuck 10 and into engagement with the turning chuck 9. The next rotation of 55 the shaft 11 turns the chuck 9 and withdraws the cup 6 from the plug 9, after which the turn table is further rotated to a position to have the glass cap ejected by means of the rod 14 and the cylinder 23 with its piston therein.

60 I claim:

1. In a glass molding apparatus, a column, a turn table journaled on the column, a plurality of molds carried by the table, means for intermittently rotating said table and a rotatable chuck for oppositely rotating and oppositely moving up and down members of separate molds simultaneously.

2. In a glass molding apparatus, a turn table, a plurality of molds carried by said table, said molds each comprising a stationary member and a relatively movable member and a rotatable chuck for moving up and down members of separate molds oppositely and simultaneously, and means for rotating the turn table.

3. In glass molding apparatus, the combination of a turn table, a plurality of molds carried by said table, and each mold comprising a movable member provided with a 75 mold actuating spindle, means operating at a certain point in the movement of the turn table to raise and lower said spindle and movable member, and a rotatable chuck for rotating the turn table and holding it in operative position.

4. In glass molding apparatus, the combination of a 80 turn-table, a plurality of molds carried thereby and each embodying a movable member, a threaded spindle by which said movable member is carried, a rotatable chuck operating on said spindle at a certain point in the movement of the turn-table to turn the spindle and raise or lower the 85 movable mold member, and means for rotating said turn table.

5. In glass molding apparatus, the combination of a 90 turn-table, a plurality of molds carried thereby and each embodying a movable mold member, a threaded spindle connected to said movable mold member, a rotary chuck adapted to engage said spindle at a certain point in the movement of the turn-table to rotate the spindle and raise or lower the movable mold member, and means for rotating said turn-table intermittently.

6. In glass molding apparatus, the combination of a 95 turn-table, a plurality of molds carried thereby and each embodying a rotary mold member having a threaded engagement with the turn-table, a rotatable chuck located at a certain point in the movement of the turn-table for revolving said rotary mold member to raise and lower the same, and means for intermittently rotating said turn-table.

7. In glass molding apparatus, the combination of a 100 turn-table, a series of molds carried thereby each embodying a rotary cup member having a threaded engagement with the turn-table, a plug or mandrel member, means located at a certain point in the throw of the table to rotate said cup member in one direction, and means located at another point for rotating said cup member in the other direction.

8. In glass molding apparatus, the combination of a 105 turn-table, a series of molds carried thereby, each comprising a rotary member having a threaded engagement with the turn-table, and simultaneously operated chucks located 110 at points in the movement of the turn-table, said chucks being adapted to engage with the rotary mold member, one to turn said mold member in one direction and the other to turn said mold member in the opposite direction, whereby by one rotary mold member is automatically elevated and 115 automatically depressed simultaneously.

9. In glass molding apparatus, the combination of a 120 turn-table, a series of molds carried thereby, each comprising a vertically movable mold member and stationary 125 mold member, rotatable chucks for automatically elevating members at certain points in the throw of the turn-table, and means for locking the turn-table at the time the movable mold members are being raised and lowered.

10. In glass molding apparatus, the combination of a 130 turn-table, a series of molds carried thereby each comprising a vertically movable cup member and a superimposed stationary plug member having an opening therethrough, and a superimposed reciprocating presser-head operated by a cylinder connected with a stationary part of the machine, said presser-head operating through the opening in 135 the fixed plug member of the mold.

11. In glass molding apparatus, the combination of a 140 turn-table, a series of molds carried thereby each comprising a vertically movable cup member, means for raising and lowering said cup member, an ejector movable through 145 the cup member, and a piston adapted to co-operate with said ejector at a certain point in the throw of the turn-table.

12. In glass molding apparatus, the combination of a 145 turn-table, a series of molds carried thereby, each embodying a vertically movable cup member, means for raising

and lowering said cup members, an ejector having the head thereof countersunk in the floor of the cup member and a stem passing through the bottom of the cup member, and a piston adapted to coöperate with said stem at a certain 5 point in the throw of the turn-table.

13. In glass molding apparatus, the combination of a turn-table, a series of molds carried thereby each embodying a vertically movable cup member, a chuck for raising and lowering said cup member, a chuck operating shaft, a 10 cylinder, a piston, and pawl and ratchet connections between said shaft and piston whereby motion is transmitted to the chuck.

14. In glass molding apparatus, the combination of a turn-table, a series of molds mounted thereon each embody-

ing a vertically movable cup member and a stationary plug 15 member, each cup member being provided with a spindle having a threaded engagement with the turn-table, a plurality of chucks for transmitting rotary motion to said spindles in reverse directions, a common chuck operating shaft, and a cylinder geared to said shaft and adapted to impart intermittent rotary motion thereto, substantially as described.

In testimony whereof I affix my signature in presence of two witnesses.

McCLELLAND MYERS.
